(57) **CLAIM**

The ornamental design for a table, as shown and described.

DESCRIPTION

FIG. 1 is a front perspective view of a table showing my new design;

FIG. 2 is a top plan view of the table of FIG. 1;

FIG. 3 is a bottom plan view of the table of FIG. 1;

FIG. 4 is a front elevation view of the table of FIG. 1;
FIG. 5 is a rear elevation view thereof of the table of FIG. 1;

FIG. 6 is a side elevation view thereof of the table of FIG. 1; and,

FIG. 7 is an opposite side elevation view thereof of the table of FIG. 1.

The broken lines illustrate portions of the table that form no part of the claimed design.
